UNITED STATES PATENT OFFICE

HARRY F. SMITH, OF DAYTON, OHIO, ASSIGNOR TO THE GAS RESEARCH COMPANY, OF DAYTON, OHIO, A CORPORATION OF OHIO

GAS-GENERATING APPARATUS

Application filed March 19, 1928. Serial No. 262,826.

This invention relates to gas generation and more particularly to the generation of gas for domestic or household use.

One of the principal objects of the invention is to provide for the production and distribution of combustible gas, particularly for domestic and household use, and for remote control of the generation and distribution.

Another object of the invention is to provide apparatus for producing such combustible gas in which the generation can be controlled from one or more distant points.

Another object of the invention is to provide a gas-generating and distributing system of this character in which the generation and distribution of the gas is automatically controlled during gas-making operation and during stand-by periods.

Still another object of the invention is to provide such gas-generating and distributing apparatus in which the generation and distribution of the gas will be automatically controlled to prevent improper functioning of the apparatus.

Other objects and advantages of the invention will be apparent from the following description when taken in connection with the accompanying drawing and appended claims.

In the drawing in which like characters of reference designate like parts throughout the several views thereof,

Fig. 1 is a front elevational view, somewhat diagrammatic, of a gas-producing and distributing system embodying this invention;

Fig. 2 is an end sectional view taken on the plane of the line 2—2 of Fig. 1;

Fig. 3 is a vertical sectional view taken on the plane of the line 3—3 of Figs. 1, 4 and 5, illustrating parts of the control apparatus; including the electrolytic switch and relay switch mechanism, and sylphon and vent valve mechanism;

Fig. 4 is a vertical sectional view taken on the plane of the line 4—4 of Figs. 3 and 5;

Fig. 5 is a horizontal sectional view taken on the plane of the line 5—5 of Fig. 4;

Fig. 6 is a view, diagrammatic in character, of the control apparatus of the gas-generating system, including a wiring diagram;

Fig. 7 is an end elevation of the control apparatus of Fig. 3, looking from the right of Fig. 3, certain parts being broken away and in section to more clearly illustrate the construction;

Fig. 8 is a side elevation, with parts broken away and in section, of a portion of the apparatus illustrated in Fig. 7, the view being taken looking from the right of Fig. 7 or from the rear of Fig. 3;

Fig. 9 is a plan view of the relay switch mechanism of the control apparatus, the view being taken looking down on the top of Figs. 3 and 4 with the cover section removed;

Fig. 10 is a horizontal sectional view of the pressure leak tube mechanism of the control apparatus taken at right angles to the plane of the line 10—10 of Fig. 1;

Fig. 11 is a view similar to Fig. 8 of a slightly modified form of sylphon control apparatus;

Fig. 12 is a partial sectional view taken on the plane of the line 12—12 of Fig. 11; and

Fig. 13 is an elevational view with parts broken away and in section of a somewhat modified form of pressure leak tube mechanism.

The invention forming the subject-matter of the present application is analogous to, and in some respects an improvement on, the invention shown in the copending applications of Harry F. Smith, Serial No. 469,976 filed May 16, 1921, and Serial No. 75,316 filed December 14, 1925.

Referring to the drawing which discloses a preferred embodiment of the invention, Fig. 1 shows a domestic or household gas-generating system comprising a gas producer or generator indicated generally at 14. This producer may be of any suitable character; but the conventional type of producer heretofore known has not been found at all satisfactory or capable of properly functioning when constructed in the small sizes which should be used for domestic or household use. Therefore, there is preferably used a producer of the character shown in applicant's co-pending application Serial No. 570,972, filed June 26, 1922.

The gas-generating system may be either pressure operated or suction operated, as desired. But preferably it is suction operated, the gas-generating system with the exception of the delivery line being under partial vacuum which prevents the possibility of leakage of gas from the gas-generating system into the surrounding atmosphere. A suitable blower 15 is provided, which may be of any conventional character; very satisfactory results have been secured with a blower comprising a centrifugal fan having radial blades revolving in a volute casing. Not only does such a blower efficiently and satisfactorily provide suitable suction for blasting the fuel bed of the producer and for forcing the generated gas under adequate pressure through the delivery line, but it is quiet in operation and lends itself nicely to control during operation. This blower is driven by suitable power means illustrated as an electric motor 16.

The inlet or suction side of the blower designated by the numeral 18 is connected to the outlet of the producer, means for cooling and purifying the generated gas being interposed between the producer and the blower inlet. Suction produced by the blower serves to draw a blast of air through the air intake 20 of the producer, this air passing through the pipe 20' into the ashpit of the base 21 of the producer where it is mixed with a suitable quantity of moisture withdrawn from a saturator chamber 28 (see Fig. 10) also positioned within the base of the producer, the blast of air and moisture passing up through the fuel bed to generate combustible gas, this being hereinafter termed "blasting". The generated gas passing off from the producer through the offtake 23 enters a radiator 24 which may be of any suitable construction to effectively cool the withdrawn gas. As shown, the radiator comprises a metallic casing having therein a centrally arranged upstanding baffle 25 to provide a constricted tortuous passage for the gas designed to bring the gas into intimate contact with the walls of the radiator to effect cooling thereof. The gas entering the radiator 24 from the offtake 23 passes up on one side of the baffle 25 to the top of the radiator, and then over the top of the baffle which is spaced from the top wall of the radiator and down on the other side of the baffle to the outlet 26. The outlet 26 discharges into a purifier indicated generally at 27. This purifier is preferably of the character of that shown in the patent of Harry F. Smith, No. 1,549,158, dated August 11, 1925, or that shown in the copending application of Harry F. Smith, Serial No. 141,544, filed October 14, 1926. The outlet of the purifier is connected to the inlet 18 of the blower.

The gas drawn from the purifier by the blower is forced from the blower casing

through the outlet pipe 30 under a desired pressure, the pressure ordinarily in household use being only a few inches of water. Connected to this outlet pipe 30 is a suitable control or vent valve mechanism indicated generally at 32 by means of which the outlet pipe may be connected either to a delivery line 33 or to a vent pipe 34. Normally when the plant is not in operation, this valve mechanism is positioned to close the delivery line and to connect the outlet of the producer to the vent pipe. If a producer of this kind is operated continuously it will of course furnish combustible gas continuously, but this tends to unnecessarily increase the cost of operation, since when none of the work devices are in use the generated gas would be wasted to the atmosphere. Consequently the gas-generating system shown herein is adapted for what may be called "intermittent operation", in that the plant operates to generate gas, generally, only during demand for gas or when gas is being used at a work device. Consequently if the plant has been standing idle,—"standing by" as it is called,—it may be necessary to blast the fuel bed at a comparatively rapid rate for a brief period in order to bring it up to good gas-making condition. During starting of the plant, and during any such blowing-up period, the blower should be connected to a vent pipe, as otherwise the incombustible products of the blasting would be forced into the house. Generally the gas producer or generator and its associated equipment will be located in the basement of the house, or in some outhouse, while the work devices, such as a gas stove indicated diagrammatically at 35, the hot-water tank, gas grates and the like, will be located in the living quarters of the house, so that the producer and the work devices may be located many feet apart. This invention provides control apparatus whereby operation of the gas-generating plant may be effected and controlled from a distant point, such for instance as from a suitable control switch 36 located at the kitchen stove, or some other similar convenient place, such control being hereinafter termed "remote control". In actual practice this switch is preferably attached directly to the manifold 37 of the stove, within which are located the various individual burner valves which control operation of the stove.

The outlet pipe 30 of the blower is connected to the inlet pipe 40 of the valve casing 41 forming a part of the vent valve mechanism 32. The casing 41 is divided by an upstanding circular partition 42 into two compartments 43 and 44. The compartment 43 is connected through the inlet opening 40 to the outlet 30 of the blower, the compartment 44 being connected by the pipe connection 45 to the house-delivery line 33. In as-

much as the centrifugal blower delivers a definite maximum pressure at maximum operating speed, the cross-section of the passage or outlet connection 45 determines the maximum amount of gas which may pass into the house-line during operation. The up-standing circular partition 42 is constructed to form a valve seat 47 upon which rests in one position of operation a disc valve 48. 5 The upper end of the casing 41 is provided with a centrally arranged opening 49. Mounted upon the upper end of the casing 41 in gas-tight relation and enclosing the opening 49 is a second casing 50, which is attached to the casing 41 by a plurality of screws or bolts 51 (see Fig. 5), suitable packing material 52 being preferably positioned between the two casings to form a tight joint. The upper casing 50 is formed with a centrally 10 arranged hollow projection 53 forming there-beneath a chamber 54 to which is connected by a pipe connection 55 the vent pipe 34. The annular lower edge of the projection 53 of the casing 50 is constructed to provide a 15 second valve seat 57 with which the disc valve 48 contacts when in its raised position. The construction is such that when the valve 48 is in its lower position and rests upon the seat 47, the producer is then disconnected from 20 the delivery line and connected to the vent pipe through the inlet opening 40, chambers 43 and 54, outlet passage 55 and vent pipe 34. When the valve 48 is in its raised position and 25 contacts with the valve seat 57, the producer is then disconnected from the vent and connected directly to the house-line 33 through the inlet opening 40, chambers 43 and 44, outlet connection 45 and delivery pipe 33. 30

The present invention provides remote control means for effecting starting of the producer gas plant and for shutting down the plant at will, and automatic means which come into play upon starting of the plant to control automatically the distribution of gas 35 in accordance with the character of the gas as to whether it is combustible or not, and to automatically maintain predetermined operating conditions within the gas delivery line, and to automatically shut down the plant and 40 otherwise safeguard the operator when abnormal conditions exist in the gas-generating system. For effecting the control of the starting and stopping of the plant at will, the remote control switch 36, which in practice is 45 preferably of the press-button type, is a two-button switch, and each button opens or closes contact through a line switch. As shown diagrammatically in Fig. 6, there is a "start" switch 60, which operates to close the proper 50 circuits to cause the blower to start operating to blast the producer, and a "stop" switch 61 which stops operation of the blower and shuts down the plant. One side of each of the 55 switches 60 and 61 is preferably grounded on 60 the stove or in any other suitable manner, as

indicated diagrammatically at 62 and 63 respectively. Also provided at the stove is a signal device 65 which may be a small electric light bulb, one side of the circuit of which is also grounded as at 66 to the stove or other suitable place, this light serving to indicate to the operator whether the plant is functioning in the proper manner, as will be presently described. 70

The other side of the "start" switch 60 is connected by a wire 68 to a coil 69 of an electromagnet forming part of a relay control switch, the construction of which is clearly disclosed in Fig. 9. The other side of the coil 69 is connected by a lead 70 to a wire 71 which in turn is connected to a wire 72 leading to one of the secondary terminals of a conventional transformer 73, the other secondary terminal of the transformer being grounded at 74. The primary terminals of the transformer are connected by wires 75 and 76 across the usual house-lighting line, indicated by the wires 78 and 79, thereby furnishing a very convenient source of electrical energy. Of course other sources of electrical energy can be used, such as storage batteries, but with the construction shown it is only necessary to plug into the usual house-lighting line. A suitable line switch 80 is provided to control the connection of the electrical circuits of the plant with the house-lighting line. While the usual 110-volt current available in the house-lighting line may be used directly in the various electrical circuits, it is preferable to use current in the control circuits of 85 much lower voltage to prevent possibility of accident and danger of fire due to faulty wiring and the like. Consequently the 110-volt current is preferably stepped down in the transformer 73 to provide a much lower voltage, usually about six volts, for operating the 90 various control circuits. 95

Associated with the electromagnet 69 is a pivoted armature 85 provided with an integrally extending arm 86 having an upturned 100 end portion 87. The armature 85 is mounted upon a pivot pin 88 carried by a metal ring 89, which is in turn mounted upon a casting 90 carried at the upper ends of screw-threaded tubes 91 and 91' which are attached at 105 their lower ends into threaded sockets 92 and 92' respectively formed within the upper casing 50. The casting 90 is thus suitably spaced from the upper portion of the casing 50 to provide room for an electrolytic switch control mechanism indicated generally at 94, which rests upon spaced lugs 93 provided on the upper surface of the casing 50. A metal jacket 95 preferably encloses the switch mechanism, the jacket resting at its lower end 110 upon an outstanding annular flange 96 formed on the casing 50, and slidably engaging at its upper end the casting 90. The casting 90 is provided with annular grooves 98 adapted to receive the lower end of a cover 115 120 125 130

casing 99 which encloses the relay control switch mechanism, the casing 99 being bolted to the casting 90 by suitable screws 100 which pass into threaded sockets 101 formed within the casting 90. Also attached to the casting 90 by screws 102 are two standards 103 which serve to support a transversely extending bar 104. Attached to the bar 104 by clamping members 104' are leaf-springs 105 and 106 which carry at their outer ends electrical contacts 107 and 108 respectively, the metal leaf-springs forming part of an electrical circuit containing the contacts 107 and 108. The contact 108 is connected by the metal spring 106 and a binding post 106' to a wire 109 which in turn is connected to one side 78 of the house-lighting line through the switch 80. The contact 107 is connected by the metal spring 105 and a binding post 105' to a wire 110 which in turn is connected to an electrode 127 of the electrolytic switch mechanism 94.

This electrolytic switch mechanism is constructed to provide non-arching contact mechanism which will effectively withstand operation in which the contacts are normally broken many times a minute without deterioration, thereby insuring long life of the apparatus. This electrolytic switch mechanism is preferably of the type described in the copending application of Harry F. Smith, Serial No. 230,881, filed November 3, 1927. As shown, the switch comprises a suitable container 115 preferably of glass which is seated upon the projection 53 of the casing 50.

The container 115 is adapted to hold a quantity of a suitable electrolyte indicated at 116. In practice it has been found that very satisfactory results are obtained where this electrolyte consists of very dilute sulphuric acid. A thin layer 117 of paraffin oil or the like is preferably flowed on top of the electrolyte on the exterior of the tube 126 to prevent evaporation. Mounted upon the top of the container 115 is a cover member 118, preferably constructed of a material which is a non-conductor of electricity, such as a rubber or resin composition. Attached to the upper side of the cover 118 is an annular metal ring 119, and attached to the inner side of the cover 118 is a second annular ring 120, this ring being preferably made of a similar non-conducting composition, suitable insulating gaskets 121 and 122 being positioned between the rings and the cover. These parts are preferably fastened together by a plurality of bolts 123 which pass through the upper metal ring 119 and through suitable openings in the gaskets 121 and 122 and cover 118 into the lower ring 120. The interior edge of the ring 120 is screw-threaded as indicated at 125 and receives thereon a tube 126, preferably of glass, the lower open end of which extends down within the electrolyte within the container 115. Mounted within the tube 126 is the electrode 127, which may be of any

suitable character, preferably a carbon electrode. As shown, the electrode 127 is fastened within the tube 126 by means of a screw 130 which passes downwardly through a metal washer 131 and through the gaskets 121 and 122 and the cover 118 and is embedded within the carbon electrode, the upper end of the screw 130 also serving as a binding post for the wire 110. Positioned within the container 115 and on the exterior of the tube 126 is a second electrode 135 which extends down adjacent the lower end of the container to be at all times immersed within the electrolyte. Preferably a quantity of granulated carbon 136 is placed within the container 115 in order to increase the effective conducting surface contact between the electrode 135 and the electrolyte. The electrode 135 is mounted on the cover by a screw 137, which screw also serves as a binding post to which is connected a lead 138 which in turn is connected to one terminal of the electric motor 16. The other terminal of the motor 16 is connected by a lead 139 to the other side 79 of the house-lighting line. This construction provides 110-volt current for the efficient operation of the electric motor, while the various control circuits are supplied with low voltage current. The electric motor circuit thus includes a main switch having contacts 107 and 108, and an auxiliary switch comprising the electrodes 127 and 135 and the electrolyte 116 in series with the main switch, both of which switches must be closed for the motor to operate.

Mounted in the cover 118 and extending down within the tube 126 is a small tube 140 which stops short of the lower end of the electrode 127. The metal ring 119 has bolted thereto a member 141 having a passage 142 therein which is in communication with the passage within the tube 140, the member 141 surrounding the upper exposed end of the tube 140 in gas-tight relation. The other end of the member 141 is provided with a bore through which extends the tube 91'. This tube is hollow providing a passage 143, which opens at its lower end into a passage 144 formed within the casing 50, and which opens at its upper end through a port 146 formed in the wall of the tube 91' into the passage 142. The passage 144 opens through a port 145 formed in the casing 41 into the inlet opening 40 connected to the discharge side of the blower. Thus the pressure on the discharge side of the blower is at all times communicated to the space within the tube 126 of the electrolytic switch by means of the port 145, passage 144, passage 143, port 146, passage 142, and tube 140. Also carried by the cover 118 is a distilled water filling tube 147 positioned on the exterior of the tube 126.

When the plant is not operating, the valve 48 will be positioned upon the valve seat 47 at the top of the partition 42 to thereby close

off communication between the producer and the house-line 33 and to open communication between the producer and the vent 34. At this time, the pressures inside and outside of the tube 126 of the electrolytic switch will tend to become balanced, since the inside of the tube is then connected to atmosphere through the passage connecting the space within the tube 126 with the inlet opening 40, the chambers 43 and 54 and the vent pipe 34, while the pressure on the outside of the tube 126 within the container 115 is at all times maintained at atmospheric pressure by means of a port 148 opening through the cover 118. Consequently the levels of the electrolyte on the inside and outside of the tube 126 will tend to equalize, the electrolyte at this time contacting with the electrode 127 as shown in Fig. 3 and thus closing the electrolytic switch through the "immersed" electrode 135. So when the "start" switch 60 is closed to start operation of the plant, this will energize the electromagnet 69 and attract the armature 85, the movement of which serves to close the contacts 107 and 108 of the main switch of the motor circuit. This is accomplished by means of a pin 150 carried by the arm 86 of the armature 85, the pin extending below the arm 86 in a position to contact with the spring 106. The pin 150 is also extended upwardly and passes through an opening formed within the cover 99 to thereby provide for manual operation of this armature and switch when desired. The auxiliary electrolytic switch being closed at this time when the main switch is closed, operation of the blower 15 is started to blast the fuel bed of the producer. Because of the positioning of the valve 48, the gas fed from the blower will pass freely through the vent to the atmosphere, the houseline remaining shut off from the blower. The vent pipe and passages are preferably provided with an orifice 148 of predetermined size to provide for a definite maximum blowing-up rate, and this is of sufficient size to give a rapid blow-up of the fuel bed of the producer upon starting or upon bringing the fuel bed up to good gas-making condition. The capacity of the blower is preferably somewhat greater than this maximum blowing-up rate, thereby insuring that the temperature of the fuel bed of the producer is rapidly brought up to a degree at which good combustible gas is generated. So long as the switch 60 is held closed and the valve 48 remains seated on the partition 42 with the blower outlet connected to the vent pipe, the blower, under the control of the electrolytic switch will continue to operate to blow in the fuel bed.

Provided in the partition 42 is an orifice or passage 151 which connects the chamber 43 with the chamber 44. Connected to the chamber 44 through the outlet connection 45

is a fluid port 152 formed in the casing 41, which port 152 is in communication with a passage 153 formed in the casing 50, the passage 153 being in turn in communication with a passage 154 formed within the hollow tube 91. The upper end of the passage 154 is in communication through a port 154' formed in the wall of the tube 91 with a passage 155' formed in the casting 90, the passage 155' opening within a chamber 155 also formed within the casting 90. The chamber 155 is enclosed at its upper end by a flexible diaphragm 156 which is clamped between the lower casting 90 and the upper metal ring 89 by means of a plurality of screws 157. Fastened to the central portion of the diaphragm is a weight 158 which at all times urges the diaphragm downwardly. The weight 158 carries an upstanding pin 159 which passes through an opening within the cover 99 to provide for manual operation when desired. Also carried by the weight 158 and preferably formed integrally therewith is an arm 160 which extends radially of the relay switch mechanism and is pivotally mounted upon a pin 161 carried in suitable bearing lugs 162 mounted upon the retaining ring 89. Attached to the arm 160 is an upstanding arm or pin 163, the arm 160 and the pin 163 thus forming in effect a bell-crank lever pivoted upon the pin 161. The pin 163 is enclosed within a loop or reverse bend of a spring 164, which spring is fastened at one end to a second pivoted armature 165. The armature 165 carries an integrally extending arm 166 which is provided with a down-turned end 168 and adjacent its end with a locking slot 167. The construction is such that when the "start" switch 60 is closed and the blower is started to blast the fuel bed of the producer and to discharge the gas under pressure through the inlet opening 40 to the vent pipe, a portion of the gas passes through the orifice 151 and builds up a pressure within the chamber 44 and associated delivery pipe 33. This pressure is communicated to the chamber 155 beneath the diaphragm 156 by the port 152, passage 153, passage 154, port 154', and passage 155'. As this pressure is built up within the chamber 155, the diaphragm 156 is raised thus rocking the end of the arm 160 about the pivot pin 161. This rocking movement causes the pin 163 to rock outwardly against the action of the spring 164, this in turn swinging the armature 165 about its pivot pin 170 carried by the retaining ring 89. The armature 85 had of course been previously rocked about its pivot 88 immediately upon actuation of the "start" switch 60 to the position shown in full lines in Fig. 9. As long as the starting button 60 is held closed, this armature 85 is held in this full-line position which serves to maintain the contacts 107 and 108 of the main switch closed against the

action of the spring 106. Should the starting button be immediately released before sufficient pressure is built up within the chamber 155, the opening of the "start" switch 60 would deenergize the electromagnet 69 and permit the armature 85 to rock counter-clockwise about its pivot 88 under the action of the spring 106, the main switch contacts 107 and 108 being thereby opened to stop the 10 operation of the blower. However, as the pressure is built up within the chamber 155 with consequent movement of the diaphragm 156 resulting in clockwise movement of the armature 165 into the position shown in full 15 lines in Fig. 9, the locking arm 166 of this armature 165 comes into locking engagement with the arm 86 of the armature 85 to thereby hold this arm in circuit-closing position, the upturned end 87 being then positioned 20 within the locking slot 167. As soon as this condition is realized, the operator may remove his finger from the switch 60, as the motor circuit is then held closed so long as the pressure within the chamber 155 is sufficiently great to hold the diaphragm up. 25 Thus a pressure operated holding means is provided for holding the main motor circuit switch closed.

The description of the starting operation 30 as set out above presupposes that the house-line is tight—has no leaks of any sort in it. When the blower is started gas will pass through the orifice 151 at a predetermined rate. If the house-line is tight the pressure 35 will accordingly build up quite rapidly in the chamber 44 and house-line, and acting through the passage connecting the chamber 44 with the chamber 155, will cause upward movement of the diaphragm 156, as described, to "hook-up" the plant,—that is to 40 latch the main motor circuit contacts closed. If, however, a valve has been carelessly left open in the house-line, or any other leak of material size exists, the limited quantity of 45 gas passing through the small orifice 151 will not be sufficient to cause a building up of pressure in the line and in the chamber 44 and consequently the diaphragm 156 will not be actuated to cause hooking-up of the mechanism. 50 If then the finger of the operator is removed from switch 60, the blower will not continue to operate, but will immediately stop; for if the contacts 107 and 108 are not latched together by the hook-up mechanism 55 they will be held in contact only so long as the electromagnet 69 is energized, and this will be only so long as the switch 60 is held closed. And the plant will refuse to operate 60 in the regular manner so long as a substantial leak exists in the house-line, which renders it "fool-proof", for the arrangement described makes it impossible for anyone to so operate the plant so long as leakage occurs. Also it inevitably indicates to the operator 65 that something is wrong.

Formed in the casing 50, as clearly shown in Figs. 3 and 5 is a second passage 175 which is in communication with a chamber 176 provided in the upper end of a coil box supporting casting 177 bolted to the casing 50 by bolts 178 receiving nuts 174. This chamber is formed beneath a flexible diaphragm 178 which is clamped between an upper rectangular surface formed on the casting 177 and a binding post cover member 179 by means of a plurality of screws 180. The diaphragm 178 carries a weight 182 which urges this diaphragm downwardly. The weight 182 is fastened to the diaphragm 178 by means of a bolt 183 and nut 184. Connected to the bolt 183 which forms one contact of a switch is a flexible wire 185 connected to a binding post 186 carried by the cover member 179. Positioned in alignment with a central opening 188 within the cover member 179 is a second contact 189 carried by a spring conductor 190 which in turn is fastened to a binding post 191. The binding post 186 is connected by means of a wire 192 to one of the primary terminals of a spark coil 194 carried by the support 177 and securely fastened thereto by means of a screw 195. The other primary terminal of the spark coil 194 is grounded to any stationary part of the apparatus as indicated at 196 in Fig. 6. The contact 189 is connected by a lead 197 to the lead 72 of the transformer to thereby supply low-voltage current to this control circuit. A cover member 198 is provided for enclosing the binding post member 179 and the wires therein, this cover being fastened in position by means of a threaded bolt 199 secured to the member 179 and receiving a retaining nut 199'. The cover 198 is provided with a suitable opening 198' through which extend the wires of the electrical circuits connected to the binding post member.

Bolted to the supporting casting 177 by means of bolts 200 is a burner casting 201. 112 This casting 201 is constructed with a hollow upper portion providing therein a chamber 202, and a lower depending leg which receives the bolts 200 and fastens the same securely to the casting 177. The upper portion of the 115 casting 201 is also provided with a circular passage 203 which is in communication through an inclined passage 204 formed in the casting 177 with the chamber 176 beneath the diaphragm 178. The outer end of 120 the hollowed portion of the casting 201 is flared upwardly and provided with a narrow elongated slot shown in dotted lines in Fig. 5 at 206, forming in effect a fan-tail burner. Carried integrally by the casting 201 is a side 125 leg 208 which carries an upstanding stationary arm 209. At its upper end, the arm 209 is bifurcated providing two spaced extensions 210, as shown clearly in Fig. 7. Positioned intermediate the upper ends of the ex- 130

tensions 210 is a tube 211 which is mounted upon a pin 212 passing through suitable aligned bores 213 formed in the upper ends of the extensions 210 and also through an aligned bore 214 in the tube 211. The tube 211 is interiorly screw-threaded and receives therein a screw 215, the end of which bears against the pin 212 to lock the parts in assembled relation. The pin 212 being rotatably mounted in the bores 213 of the extensions 210, the tube 211 is thus provided with a pivotal connection at the upper ends of the extensions 210. The other screw-threaded end of the tube 211 receives the exteriorly screw-threaded end of a stem 218 of an expandable and contractible sylphon 219. This sylphon comprises a hollow corrugated metal cylinder, preferably of copper, the ends of which are closed by plates 220 fastened thereto such as by welding in gas-tight relation. The plate 220 at one end carries the stem 218, while the opposite plate 220 carries a second threaded stem 222 which extends through a bore 223 formed in one side of a sylphon casing 224 and is rigidly fastened to the sylphon casing 224 by means of nuts 225 threadedly received on the stem 222. The sylphon casing 224 comprises an elongated member U-shaped in cross-section, as shown clearly in Fig. 7, which is pivoted at one end upon a pin 227 passing through aligned bores 228 formed in the extensions 210 and through aligned bores 229 formed in bearing lugs on the casing 224. The pin 227 is clamped by a screw 230 passing through a threaded counterbore formed in one of the extensions 210, against rotation with respect to the extensions 210, the casing 224 being constructed to rock about the pins 227. The outer ends of the pin 227 are provided with enlarged heads 231 to prevent side play of the pin.

The construction is such that the burner slot 206 is positioned beneath the sylphon 219. One end of the sylphon 219 is rigidly fastened to the pivoted casing 224, while the other end of the sylphon is pivotally mounted on the stationary arms 210. Consequent expansion of the sylphon with an increase in its effective length results in rocking the casing 224 clockwise about its pivot pin 227 to thereby increase the effective distance between the pivot pin 212 to which one end of the sylphon is attached and the connection 223 to which the other end of the sylphon is attached. Conversely, contraction of the sylphon rocks the casing 224 counter-clockwise about its pivot pin 227. Counter-clockwise movement of the casing 224 is limited by a stop 234 which is screw-threadedly mounted within the arm 208, a locking nut 235 being provided to lock the stop 234 in adjusted position. This stop engages an end extension 237 of the casing 224.

The opposite end of the casing 224 is pro-

vided with a second extension 238 which is positioned to contact upon clockwise rocking movement of the casing 224 with the end of an actuating lever 240 fastened to the vent valve 48. As shown, the casing 50 is provided with a bore 241 through which the lever 240 extends, and within which the lever is pivoted by a ball pivot 242. The inner end of the lever 240 is pivotally mounted upon a pin 243 which is fastened within two spaced upstanding lugs 244 carried by the valve 48. The diameter of the outer end of the bore 241 is materially larger than the diameter of the lever 240 to permit of rocking movement sufficient in extent to raise the valve from its seat upon the partition 42 and to bring it into contact with the valve seat 57 to thereby close off communication between the producer and the vent pipe 34, and to open communication between the producer and the house-line 33. The outer end of the bore 241 is closed by means of a handle guide member 246 fastened to the casing 50 by screws 247, the guide member also having a bore through which the handle passes. On the outer end of the handle is fastened by a nut 247' a grip member 249. Lubrication of the ball pivot 242 provides for easy manipulation of the vent valve and also effectively seals the bore 241 against the leakage of gas. Expansion of the sylphon 219 thus produces a rocking movement of the casing 224 sufficient to bring the extension 238 into contact with the member 249 and to effect bodily movement of the vent valve 48 to close communication between the producer and the vent pipe and to open communication between the producer and the house-line. Contraction of the sylphon on the other hand rocks the casing 224 out of the path of the grip member 249 and permits the valve 48 to drop upon its lower seat to close communication between the producer and the house-line and to open communication between the producer and the vent pipe. Manual operation of the vent valve is also permitted as desired through the agency of the exposed grip member 249. The construction is such that when the valve 48 is once raised, the normal pressure of the gas passing through the casing under the action of the blower 15 is sufficient to maintain the valve in its raised position.

One of the secondary terminals of the spark coil 194 is connected by a lead 250 to a spark-plug 251 having a point 252 suitably spaced from the point 253 of a second spark-plug 254. The plugs 251 and 254 are mounted within suitable openings in flanges 255 formed integral with the casting 201 and extending outwardly at right angles to the side leg 208. A second supporting plate 256 provided with openings receiving the smaller ends of the plugs is bolted to the lower side of the casting 201 by means of a bolt 257, the

larger portions of the plugs resting on the supporting plate 256 and contacting with the flanges 255, thereby holding them in fixed position. The construction is such that the 5 points of the spark-plugs are positioned directly above the burner slot 206 of the bypass burner beneath the sylphon 219. The other secondary terminal of the spark-coil 194 is grounded as indicated at 259. Only 10 a single spark-plug need be used, the point of which is suitably spaced from a ground contact. However, the construction shown is used when it is desired to ignite the gas issuing from a second burner 260 (see Fig. 15 6) at the same time, the second plug 254 being connected by a wire 263 with a spark-plug 264 located at the burner 260 and having its point 265 positioned in spaced relation to the burner and grounded thereby. 20 The burner 260 may be associated with any suitable work device, such as a domestic hot-water heater, and is preferably connected with the source of supply of generated gas by a pipe 261, connected to the discharge 25 side of the blower 15 at any suitable point such as the inlet pipe 40 or the valve chamber 43. A valve 262 is provided in the pipe 261 whereby the burner 260 may be turned on or off as desired, and the supply of gas 30 to the burner may be controlled. The casting of a domestic hot-water heater is indicated in Fig. 1 at 266, and a water coil at 267, which coil may be connected to a hot-water storage tank (not shown) in a well-known manner.

In operation, after the "start" switch 60 is closed and the plant is hooked up, assuming the delivery main to be gas-tight, a portion of the gas discharged by the blower 15 into the 40 chambers 43 and 54 of the valve casing passes through the passage 175 into the chamber 176 beneath the diaphragm 178, producing a gas pressure therein. This pressure raises the diaphragm 178 and brings the contact 183 into 45 engagement with the spaced contact 189 to close the primary circuit of the spark-coil 194. This energization of the spark-coil produces a current in the secondary circuit with the result that sparking is produced at the 50 spark-plugs 251 and 254 and also at the plug 264. The gas passing into the chamber 176 escapes through the passages 204 and 203 into the burner chamber 202 where it issues through the burner slot 206. As soon as the 55 gas becomes combustible, it ignites, and the burning of this gas beneath the sylphon 219 rapidly heats this expansible member. The sylphon is preferably provided with a liquid which vaporizes readily upon the application 60 of heat to give a rapid pressure rise within the closed sylphon chamber. Any suitable liquid may be used for this purpose, very satisfactory results being secured with water. Therefore, as soon as the gas becomes of good combustible quality and burns freely from the

burner slot 206, a gas pressure is rapidly formed within the sylphon 219 which rocks the sylphon casing 224 about its pivot pin 227 and moves the handle 240 of the vent valve 48 to shift this vent valve into position to connect the producer with the house line 33. Thus the plant is automatically shifted to disconnect the producer from the vent pipe and to connect the producer to the house line when the gas becomes combustible. At the same time, 70 as soon as the gas becomes combustible, the burner 260 is ignited to provide heat for its associated work device during operation of the plant. As the vent valve is thus shifted, the supply of gas is automatically cut off to the sylphon burner 206, while the supply of gas to the burner 260 is maintained. As gas is no longer being discharged through the bypass 175 to the sylphon burner, the weight 182 causes the diaphragm 178 to drop to break the contacts 183 and 189, so that the igniting means is automatically rendered inoperative as the vent valve is shifted.

When the points of the spark-plugs 251 and 254 are positioned so that continuous sparking takes place directly beneath the sylphon 219 when the contacts 183 and 189 of the spark-coil circuit are closed, it is found that this incessant sparking produces some combustion of the gas even though the gas is not yet in a 90 condition to maintain combustion of itself without the aid of the incessant sparking. The result is that the sylphon may be prematurely heated and throw the vent valve 48 before the gas becomes of good combustible 95 quality. To prevent such an occurrence, a construction such as shown clearly in Figs. 7 and 8 is provided. The points of the spark-plugs are positioned to one side of the sylphon 219 above an extended end of the burner slot 206. Between the plugs and the sylphon and above the burner slot is mounted a baffle 268, which baffle is carried by the casting 201. The lower end of the baffle 268 is slightly spaced from the burner slot 206. With this 100 construction, the incessant sparking of the plugs does not prematurely affect the sylphon 219, the heated products of combustion resulting from the sparking passing off through the slots 269 formed in the upper portion of the sylphon casing 224 without coming in direct contact with the sylphon. However, as soon as the gas becomes of good combustible 105 quality, it will flash down beneath the baffle 268 and ignite the gas issuing from the burner slot 206 on the far side of the baffle, and the burning gas will then directly affect the sylphon 219 to automatically throw the vent valve 48. The slots 269 in the sylphon casing 110 115 120 125 130 135 224 not only provide effective circulation of the products of combustion upwardly through the casing about the sylphon, but also permit rapid circulation of cooling air through the casing when gas is not being supplied to the sylphon burner. The metal of the sylphon

being of high conductivity, rapid cooling due to such convection air currents results, so that the sylphon casing 224 due to contraction of the sylphon is rapidly returned to position 5 which permits dropping of the vent valve.

If no leak is present, the hook-up mechanism will function after a short interval,—normally a few seconds—to latch the main motor contacts shut. The automatic sylphon 10 mechanism will then function to automatically shift the vent valve to connect the producer to the house-delivery line when the gas becomes combustible, the time required for this operation depending upon the condition 15 of the fuel bed at the commencement of the blowing in, but being usually accomplished in two or three minutes and often in as short a time as one minute. In order that the operator, located at a distance from the plant, 20 may know that the plant is functioning normally after he has closed the "start" switch 60, an indicating mechanism is provided. As shown in Figs. 1 and 6, this indicating mechanism may consist of any electric light bulb 25 65 positioned adjacent the remote control switch 36. As soon as the "start" switch 60 is closed and the blower is operating to create a pressure within the vent valve chamber 54 sufficient to close the contacts 183 and 30 189 of the primary circuit of the spark-coil, this fact will be indicated to the operator by a flashing of the light 65 which is connected in parallel with the spark-coil 194 by a lead 270. Thus closing of the contacts 35 183 and 189 supplies current from the transformer 73 through the wires 72 and 197, contacts 189 and 183, and wires 192 and 270 to the indicating light 65 and thence to ground at 66. In actual operation, therefore, the 40 operator merely presses the button to close the switch 60 and holds the same closed for a few seconds until the indicating bulb 65 is lighted. Upon releasing the button of the switch 60, if the hook-up mechanism has not 45 been actuated to hook up the plant, then the main motor circuit contacts 107 and 108 will be opened to stop the blower 15, and the reduction in pressure will permit the diaphragm 178 to fall to break the contacts 183 and 189, and the signal light 65 will go out 50 almost immediately. This will warn the operator that either sufficient time was not given for the hook-up mechanism to function, or else that the plant is not functioning normally 55 and that a leak exists in the house-line. If upon again actuating the starting button for the normal length of time, the plant fails to hook up as indicated when the signal light 65 goes out, the operator is thus 60 assured that a leak exists in the house-line, and that the plant may not be started until such leak is closed. The operator is thus safeguarded against possible accidents resulting from a leak. If the plant is operating 65 normally and the hook-up mechanism has

functioned by the time the operator releases the button of the "start" switch 60, the main motor contacts will then be locked in closed position, and the blower will continue to blow in the fuel bed. The pressure beneath the diaphragm 178 will therefore be maintained, and the signal light 65 will remain lighted during this blowing-up period, the operator being apprised that the plant is functioning normally. As soon as the gas becomes combustible, the sylphon mechanism automatically shifts the vent valve, the contacts 183 and 189 are opened, and the signal light 65 goes out. The operator is then apprised that gas is being supplied to the delivery line, and the work devices connected thereto may be started. As long as the light 65 remains lighted, the operator knows that the motor operated blower is functioning and that gas is being discharged to the vent pipe. An indicator visible from the remote control switch is thus provided which indicates to the operator the positioning of the vent valve.

As described, the weight and proportions of the valve 48 are so arranged that when lifted against its upper seat 57 it will be held there by the normal pressure of the gas. But if the pressure within the house-line 33 falls sufficiently the weight of the valve will no longer be sustained and the valve will fall onto its lower seat 47 to again connect the blower to the vent pipe. The arrangement is such that the pressure normally attained in the house-line during normal operating conditions is sufficient to hold the valve against the seat 57; but if there is a sufficiently abnormal drop in this pressure then the valve will fall and the work device connected to the house-line will be cut off from utilization of gas. Furthermore, the weight 158 attached to the diaphragm 156 is so proportioned that an abnormal drop in pressure in the delivery line 33 will permit the weighted diaphragm 156 to fall to thereby release the holding means or locking arm 166 and permit the main motor contacts 107 and 108 to be opened to stop the blower and shut down the plant. Thus if the plant is unduly overloaded during operation, the pressure in the delivery line will drop and the plant will be automatically shut down, whereby inadequate functioning of the work devices or overloading of the producer is entirely prevented. Furthermore, after such overloading has resulted in shutting down the plant, restarting of the plant can be effected only through manual intervention.

This described construction also provides another protective feature,—prevention of automatic restarting of the plant after an abnormal interruption of the electric current in the supply line or a failure of the power source. If this current should be interrupted for an appreciable time while gas is being utilized at a work device, the blower motor

would stop irrespective of the positioning of the auxiliary contacts, and consequently the flame would be extinguished at any open burner due to the failure of the gas supply.

5 If the hook-up mechanism should remain undisturbed the motor would restart upon the resumption of current flow through the house-line and the house would be filled with gas. But this can not happen with these controls. For when the house-line current fails, pressure within the house-line will of course also fall, one or more burners being open. Pressure beneath the diaphragm 156 will then fall and the weight 158 will move 10 the diaphragm to a position which rocks the pin 163 inwardly against the spring 164, thereby rocking the locking arm 166 counterclockwise about its pivot 170 to the dotted-line position shown in Fig. 9, to thereby 15 release the arm 86 which is then moved by the spring 106 to the dotted-line position shown in Fig. 9 to permit opening of the main motor circuit contacts 107 and 108. The 20 valve 48 will then be no longer sustained by the pressure of the gas but will drop onto the partition 42 to connect the blower to the vent pipe. And so when current flow through the 25 house-line is resumed the motor switch is open, the producer is connected to the vent pipe, and the motor can not start until there has been outside intervention,—such as the 30 operator starting in the normal manner.

The blower at its normal rate of operation 35 delivers gas at such a rate that there is a tendency for the pressure in the valve casing to continue to build up when the producer is connected to the house-line 33. As this 40 pressure increases it acts through the passage including the port 145, passage 144, passage 143, port 146, passage 142 and tube 140 to affect the pressure existent within the tube 126 upon the top surface of the electrolyte 116, and forces the electrolyte downwardly and out into the container 115. As the pressure 45 continues to build up, the electrolyte is forced downwardly below the lower end of the electrode 127 to break the motor circuit. With consumption of gas at a work device, the pressure then falls within the delivery line and inlet opening 40, which falling pressure is communicated to the space within the tube 126 with the result that the electrolyte rises again into contact with the electrode 127 to again make the motor circuit. The relative 50 arrangement and proportioning of the parts is such that when the pressure has dropped sufficiently to permit the electrolyte to again contact with the electrode 127, this pressure is still sufficiently high to hold the diaphragm 156 in its upper position to maintain the main motor circuit contacts 107 and 108 latched in closed position, and to hold the vent valve 48 up against its seat. As the pressure in the delivery line rises, therefore, above a predetermined normal the current in the motor cir-

cuit is interrupted; and as the pressure falls the motor circuit will be again closed as soon as the electrolyte comes in contact with the electrode 127. Thus a continuously intermittent energizing of the operating motor will occur during use of the device. Under normal gas-using conditions the current to the motor and operation of the blower is normally interrupted a number of times a minute, as many as twenty to thirty times a minute, with the result that the effective pressure in the delivery main 33 is maintained substantially constant. In actual operation the movable parts of the motor and blower generally do not cease movement, for the contact mechanism is responsive to slight pressure fluctuations and therefore the breaking of the motor circuit as the normal pressure is exceeded is so brief that inertia of the motor and blower parts will cause continued rotation thereof. And the practical effect is to secure a substantially uniform gas pressure, with a very accurate and simple control for motors of conventional construction and characteristics.

When it is desired to terminate operation of the plant for a period, the button of the "stop" switch 61 is pressed to close that switch, which acts through a conductor 275 leading to a coil 276 of a second electromagnet also mounted upon the retaining ring 89 of the relay switch mechanism. The circuit of the electromagnet 276 is completed through a lead 277 which is connected to the common return wire 71 for both magnets 69 and 276 and the wire 72 to the transformer 73. The electromagnets 69 and 276 are preferably mounted upon a base plate 278 which is fastened to the retaining ring 89 by means of a plurality of screws 279. Energization of the electromagnet 276 attracts the pivoted armature 165 to thereby swing the locking arm 166 into its dotted-line releasing position, as shown in Fig. 9, to thereby permit the main motor circuit contacts 107 and 108 to be 100 opened to shut down the plant. If desired, the plant may be shut down manually by pushing down the pin 159 which moves the diaphragm 156 downwardly and through the medium of the arm 160 and pin 163 also effects releasing movement of the locking arm 166. The plant may also be started by moving the pin 150 to swing the arm 86 into full-line position to hold the contacts 107 and 108 closed.

In ordinary household use, the plant may stand idle for considerable periods, overnight for example. Or the gas may be used for heating the water in the hot-water system in which case there is a continuous load on the producer and the fuel bed is thus maintained in good gas-making condition so that it immediately responds to increased load to give any desired quantity of good gas within its capacity. But where the producer stands

idle for any considerable period, the ignited fuel may cool below incandescence so that it may be necessary to blow in the fuel bed afresh before good combustible gas in quantities 5 may be secured. This may make necessary a wait of several minutes before suitable gas is secured, and would also make necessary igniting kindling material in the producer itself. In order that the fuel bed may be at 10 all times maintained in suitable condition, even during considerable standby periods, means is provided whereby the blower is automatically operated at intervals to cause a short blowing in of the fuel bed to maintain it alight, thus permitting remote control 15 at all times.

This means is shown clearly in Fig. 3 in which the control mechanism is provided with a third electrode 280, which is similar to 20 the electrode 127, but is of somewhat less length. The electrode 280 is mounted to the cover 118 within the tube 126 by means of a screw-binding post 282. Provided in the gaskets 121 and 122 and the cover 118 are 25 aligned openings indicated at 283, and the metal ring 119 is also provided with an aligned bore within which is mounted the end of a tube 284. There is thus formed a passage which communicates with the space 30 within the interior of the tube 126. The tube 284 leads to an orifice member 285, shown in Fig. 10, which contains an orifice of controlled size opening to atmosphere to thereby 35 permit the escape of the gas pressure within the tube 126 at a controlled rate. This orifice member 285 may be of any suitable character; but in practice a piece of thermometer tubing 40 functions very satisfactorily. During operation the tube 126 will be so filled with gas that the level of the electrolyte is at approximately the lower end of the electrode 127, termed the "running" electrode. But when the plant is shut down or standing by, the electrolyte rises within the tube 126 until it 45 contacts with the lower end of the tube 140 which then shuts off communication of the space within the tube 126 with the vent pipe. The lower end of the tube 140 extends somewhat below the lower end of the electrode 50 280, termed the "standby" electrode. Therefore, as the electrolyte covers the lower end of the tube 140, gas is trapped within the tube 126 which is not permitted to escape except by passing through the orifice member 285. 55 And the effective area of that orifice is such that after a predetermined interval gas will have escaped sufficiently to permit the electrolyte to move upwardly in the tube 126 to contact with the electrode 280.

60 This electrode 280 is connected by means of a conductor 287 with the side 78 of the houselighting line, the arrangement being such that as the electrolyte contacts with the electrode 280 the motor is energized to start the blower to cause blowing-in of the fuel bed.

But the motor will run for only a brief period as its operation builds up pressure within the passage 40 which is communicated to the tube 140 and space within the tube 126 to again depress the electrolyte within the tube 126 to 70 break contact of the electrolyte with the electrode 280. The blowing-in period may be of such length as desired but ordinarily is just sufficient to liven up the fuel bed and keep it 75 alight. The intervals between these periodic blastings will depend upon the time necessary for the gas leakage from the tube 126 to permit closing of the by-pass circuit, and this depends on the size of the tube 126, the 80 extent of necessary electrolyte rise therein, and the effective area of the orifice. In actual practice very satisfactory results have been secured where these blastings occur at about five-minute intervals; but the intervals between them may be regulated to suit operating 85 conditions. Because of the normal standby positioning of the vent valve 48, the gas resulting from such periodical blasting will be discharged to the vent pipe. The electrical motor circuit including the electrode 90 280 forms a shunt circuit about the main motor circuit contacts 107 and 108.

The generated producer gas contains some water vapor, which may condense within a very small orifice member such as the member 285, resulting in stoppage of the orifice and improper functioning of the intermittent blow-up mechanism. To prevent such a contingency, means are provided for preventing 95 any possibility of condensation of moisture within the orifice member 285. This is accomplished in the form of invention disclosed clearly in Fig. 10 by positioning the orifice member 285 within a heated atmosphere 100 which is above the condensation point of such water vapor. As shown, the orifice member is positioned within the saturator chamber 28 formed within the base 21 of the producer. As shown clearly in Figs. 1 and 10, the pipe 105 284 extending from the electrolytic switch leads to a casting 293 which is positioned on the exterior of the base 21 of the producer 14. The casting member 293 is fastened to a second casting 294 by means of screws 295. The 110 second casting member 294 is formed with a cylindrical projecting end 296 which extends through the wall of the base 21 of the producer into the steam space of the saturator chamber 28. A portion 297 of enlarged diameters of the cylindrical projection 296 is screw-threadedly received within a threaded bore 298 passing through the wall of the base 21. The casting 293 is hollow, forming therein a 115 condensate chamber 300. The orifice tube 285 communicates with the upper end of the chamber 300, this tube in turn discharging into a surrounding annular passage 302 formed between the orifice tube 285 and the inner wall of the cylindrical extension 296. The orifice tube 285 is held in position by means of 120 125 130

a rubber sleeve 303, which serves to prevent injury to the fragile tube 285 and also prevents leakage from the chamber 300 directly into the annular passage 302. On the exterior of the base 21, the casting 294 is provided with a plurality of radial ports 304 which provide communication of the passage 302 with the atmosphere. In operation, gas passes from the tube 284 into the chamber 300, where some of the water vapor contained therein is condensed, this water flowing to the bottom of the chamber or trap from where it may be removed from time to time by means of a drain plug 305. The gas passes from the chamber 300 at a controlled rate through the orifice tube 285, where due to the heating effect of the steam within the saturator chamber any condensation of water vapor still retained within the gas is prevented. The gas then flows through the annular passage 302 to the ports 304 where it escapes into the atmosphere.

Means are provided for supplying water to the saturator chamber 28 of the producer in accordance with the demand for fresh water due to the vaporization to form steam for the blast. This means comprises a water container 310, shown clearly in Figs. 3 and 4, which is pivotally attached to depending lugs 311 extending from the casing 41 on opposite sides of the container 310. This water container 310 has a depending pocket 313 into which extend two drain pipes 314 and 315 which drain off from the chambers 43 and 44 respectively any moisture which may condense therein. The container 310 is connected by means of a flexible pipe 316 to a water inlet connection 317 feeding into the saturator chamber 28 in the base 21 of the producer. Water is supplied to the container 310 through the pipe 318 fixedly supported in a threaded bore 319 formed in an extension 320 integrally carried by the casing 41. The pipe 318 leads into a nozzle 321 the lower end of which opens into the container 310. Carried by the container 310 adjacent the end of the nozzle 321 is a valve member 322, which is moved toward or away from the opening in the nozzle 321 as the container 310 swings about its pivotal supports 311. The water in the container tends to swing the container about its pivotal supports in a clockwise direction as shown in Fig. 3. The container 310 is provided with a projection 323 upon which is adjustably mounted a balance weight 324. This balance weight tends to counterbalance the tendency of the water to swing the container in a clockwise direction to move the valve 322 toward the nozzle 321 to shut off the supply of water to the container. By reason of this arrangement, the positioning of the valve 322 with respect to the open end of the nozzle 321 varies according to the quantity of water within the container. Of course the greater the load upon the producer

the more rapid the vaporization of the water in the saturator to form steam which is incorporated with the air of the blast, and therefore the greater the quantity of water that must flow from the container 310 through the pipe 316 to the saturator. This pivotal mounting and counterbalancing of the container 310 results in such motion of the container that the valve 322 is moved away from the nozzle to permit a greater flow of water when the water level falls, and is moved toward the nozzle to cut down the flow of water when the water level rises.

The vent pipe 34 discharges to atmosphere on the exterior of the building, generally through a chimney, or the pipe may be extended to the exterior. During standby periods of the producer, particularly in cold weather, a back-flow tends to occur in the vent pipe, which tends to force gas and air back into the producer. To prevent this, an outwardly opening check valve 325 is positioned within the vent pipe 34. This valve may be an ordinary flap valve pivoted at one side of the pipe as at 326 so as to open outwardly under pressure of gas being discharged to the vent pipe during blowing in of the fuel bed, and to seat by gravity to close the pipe during standby periods to prevent any back flow through the vent pipe. In order to prevent gas within the producer system from backing into the ash pit and thence through the air-inlet opening 20 out into the room in which the producer is situated, an inwardly opening check valve 327 is provided in the air-inlet connection. As shown, the check valve 327 is a flap valve pivoted at 328 to the casing 20 so as to close by gravity the open face 329 of this casing constituting the air-inlet opening. Thus when suction is created in the producer by operation of the blower, air for the blast passes freely past the inwardly opening flap valve 327, but during standby periods the valve closes by gravity to prevent any back flow through the air-inlet connection. This construction not only prevents back draft through the system, but also serves to hold the fire or heat of the incandescent fuel bed within the producer for longer intervals, so that less frequent intermittent blastings during standby periods serve to maintain the fuel bed in good gas-making condition.

In Figs. 11 and 12 is shown a somewhat modified sylphon valve-shifting construction adapted to automatically disconnect the producer from the vent pipe and to connect it to the house-delivery line when the gas becomes combustible. In this form of the invention, the sylphon 219' is provided with a stem 330 which extends through a flared opening 331 in the upstanding arm 332 of the stationary casting 201' to which the sylphon casing 224' is pivotally connected by means of a pin 227'. The end of the stem 330

of the sylphon is retained in position within the opening 331 by means of a washer 334 and screw 335 which is received within the hollow threaded bore of the stem 330, the stem being 5 otherwise freely movable within the bore. The flared opening 331 permits the pivotal rocking movement of the sylphon 219' and sylphon casing 224' upon the expansion and contraction of the sylphon in the manner previously described, to shift the actuating lever 240' of the vent valve. In this form, means are provided for preventing movement of the sylphon casing 224' until the sylphon 219' has expanded to a sufficient degree to cause a very 10 rapid and positive actuation of the lever 240' when this locking means is released. This comprises a locking lever 338 pivotally mounted upon a pin 339 fastened in the walls of the sylphon casing 224'. This lever has a slot 15 340 forming a latching projection 341 adapted to cooperate with the upper end of the rigid arm 332. The lever 338 also has a depending arm 342 which is bifurcated at its lower end and straddles the stem 330 of the 20 sylphon 219' and is adapted to bear against the end closure member 220' of the sylphon as indicated at 343. Mounted upon the stem 330 and bearing against a collar 344 abutting the stationary arm 332 at one end, and bearing 25 against a collar 345 bearing against the closure 220' of the sylphon at the other end is a spring 346.

In operation, when the sylphon burner 206' is ignited by means of the spark plugs 251' 30 and 254' in the manner previously described, the burning of the gas rapidly heats the fluid within the sylphon 219' producing an expansion and a lengthening of the sylphon casing. The one end of the sylphon casing 219' is rigidly fastened as at 348 to the sylphon casing 224'. Consequently, lengthening of the sylphon casing 219' moves the opposite end 220' and associated stem 330 toward the stationary arm 332, the end of the stem sliding 35 through the bore 331 to permit such movement. This expansion movement rocks the arm 342 of the locking lever 338 clockwise, and when the sylphon has sufficiently expanded the locking lever is released from the upper end of the stationary arm 332, and the stored-up energy of the sylphon 219' and the tension of the spring 346 serve to rock the sylphon casing 224' about its pivotal connection 227' to positively throw the actuating arm 240' of the vent valve. An adjustable stop 350 is theadedly mounted within the wall of the sylphon casing 224' in position to contact with the upper end of the stationary arm 332 to limit the extent of rocking movement of the sylphon casing. Upon cooling of the sylphon and contraction thereof, the casing 224' is rocked counter-clockwise against the action of the spring 346 to resume its former position. The end of the locking lever 338 is beveled as indicated at 351 to permit this

lever to ride over the upper beveled end 352 of the stationary arm 332 to resume its locking position.

In Fig. 13 is shown a slightly modified form of leak tube construction for the electrolytic switch mechanism 94'. In this form, leak tube 284' leading off from the space within the tube 126 of the electrolytic switch has a downwardly extending portion 354 connected to a condensate trap 355 which is formed as hollow casting having a condensate chamber 356 therein provided with a drain plug 356'. Leading off from the upper end of the condensate chamber is an upwardly extending tube 357 provided with a reverse bend 358, which is connected by a rubber connection 359 with a piece of thermometer tubing 285', providing the controlled orifice for the escape of gas from the electrolytic switch. The condensate chamber 356 and the two upwardly extending tubes 354 and 357 which drain back into the condensate chamber serve to effectively condense and remove water vapor from the gas to prevent the stoppage of the fine bore or orifice in the member 285'.

While the forms of apparatus herein described constitute preferred embodiments of the invention, it is to be understood that the invention is not limited to these precise forms of apparatus, and that changes may be made therein without departing from the scope of the invention which is defined in the appended claims.

What is claimed is:

1. A gas generating system comprising a gas producer, a gas offtake leading from said producer, a vent pipe connected with said offtake, a delivery main connected with said offtake, and automatic means for controlling communication of said offtake with said vent pipe or with said delivery main in accordance with the quality of the generated gas, said automatic means comprising a valve, a burner, means for supplying generated gas to said burner, an expandible and contractible sylphon responsive to heat generated by the burning of gas at said burner, and an operative connection between said sylphon and said valve whereby movement of said sylphon effects shifting movement of said valve.

2. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, means for supplying generated gas to said burner, an expandible and contractible sylphon positioned to be heated by the burning of gas at said burner, a pivotally mounted sylphon casting, an operative con-

nection between said sylphon and said casing whereby expanding and contracting movement of said sylphon produces rocking movement of said casing about its pivot, and an actuating lever for said valve positioned to be contacted by said casing on rocking movement thereof to effect shifting of said valve.

3. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, means for supplying generated gas to said burner, an expandable and contractible sylphon responsive to heat generated by the burning of gas at said burner, an operative connection between said sylphon and said valve whereby movement of said sylphon effects shifting movement of said valve, and means for restraining actuating movement of said sylphon until sufficient energy is stored therein to effect a sudden shifting movement of said valve.

4. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, means for supplying generated gas to said burner, an expandable and contractible sylphon responsive to heat generated by the burning of gas at said burner, a stationary support for one end of said sylphon, a sylphon casing pivotally mounted on a stationary support, a connection between the other end of said sylphon and said sylphon casing, the pivotal mounting of said casing and the stationary support for said one end of the sylphon being so spaced that expanding and contracting movement of said sylphon effects rocking movement of said casing about its pivotal mounting, an actuating lever for said valve positioned to be contacted by said casing on rocking movement thereof to effect shifting of said valve, locking means for restraining actuating movement of said casing during initial expanding movement of said sylphon, and means responsive to a predetermined expanding movement of said sylphon to release said locking means to thereby effect a sudden shifting movement of said valve.

5. A gas generating system comprising a gas producer, a gas offtake leading from said

producer, a vent pipe connected with said offtake, a delivery main connected with said offtake, and automatic means for controlling communication of said offtake with said vent pipe or with said delivery main in accordance with the quality of the generated gas, said automatic means comprising a burner, means for supplying generated gas to said burner, means coacting with said burner adapted to effect opening of communication between the said offtake and said delivery main and closing of communication between the said offtake and said vent when the gas issuing from said burner becomes combustible and burns, said automatic means having mechanism for automatically cutting off the supply of gas to said burner when said means operates to effect opening of communication between the said offtake and said delivery main and closing of communication between the said offtake and said vent.

6. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, means for supplying generated gas to said burner, means coacting with said burner adapted to effect shifting movement of said valve when gas issuing from said burner becomes combustible, and pressure actuated igniting means operably responsive to pressure within said vent pipe for igniting the gas issuing from said burner.

7. Gas generating apparatus of the character described, comprising a gas producer having a fuel bed, a pump for blasting the fuel bed of said producer to generate combustible gas, a valve casing connected to the outlet side of said pump, a gas distributing line leading off from said casing, a vent pipe leading off from said casing, a valve within said casing tending to move toward position to close off the distributing line from the outlet of the pump, and automatic means for shifting said valve to open connection between the distributing line and said pump outlet and close connection between the vent pipe and said pump outlet, said automatic means comprising a by-pass leading off from said casing on the vent pipe side of said valve, a burner connected to said by-pass, means coacting with said burner adapted to effect shifting movement of said valve when gas issuing from said burner becomes combustible and burns, igniting means for said burner, and pressure-actuated means responsive to pressure within said by-pass for controlling the operation of said igniting means.

8. Gas generating apparatus of the charac-

ter described, comprising a gas producer having fuel bed, a pump for blasting the fuel bed of said producer to generate combustible gas, a valve casing connected to the outlet side of said pump, a gas distributing line leading off from said casing, a vent pipe leading off from said casing, a valve within said casing tending to move toward position to close off the distributing line from the outlet of the pump, and automatic means for shifting said valve to open connection between the distributing line and said pump outlet and close connection between the vent pipe and said pump outlet, said automatic means comprising a bypass leading off from said casing on the vent pipe side of said valve, a burner connected to said bypass, a sylphon coacting with said burner and adapted to be actuated when gas issuing from said burner becomes combustible and burns, an operative connection between said sylphon and said valve whereby actuation of the sylphon effects shifting movement of the valve, electric igniting means for said burner, and a pressure operated control switch in the circuit of said igniting means responsive to pressure within said bypass and adapted to be closed only when gas is being discharged through said bypass.

9. Gas generating apparatus of the character described, comprising a gas producer having a fuel bed, a pump for blasting the fuel bed of said producer to generate combustible gas, a valve casing connected to the outlet side of said pump, a gas distributing line leading off from said casing, a vent pipe leading off from said casing, a valve within said casing tending to move toward position to close off the distributing line from the outlet of the pump, whereby when said valve is moved to open connection between the distributing line and said pump outlet and to close connection between said vent and said pump outlet the valve is held in such moved position by the normal pressure of gas passing through said valve casing, and automatic means for shifting said valve, said automatic means comprising a sylphon, a burner positioned to heat said sylphon, means for supplying generated gas to said burner, and means for automatically shutting off the supply of gas to said burner when said sylphon is actuated to shift said valve, whereby said sylphon then cools, and releases said valve, so that the latter may move to again close off the distributing line and open the vent pipe when the pressure of said delivered gas falls to a predetermined minimum.

10. A gas generating system comprising a gas producer, a gas offtake leading from said producer, a vent pipe connected with said offtake, a delivery main connected with said offtake, and automatic means for controlling communication of said offtake with said vent pipe or with said delivery main in accordance

with the quality of the generated gas, said automatic means comprising a sylphon, and a casing for said sylphon having circulation openings therein to facilitate the passage of convection currents over said sylphon.

11. A gas generating system comprising a gas producer, a gas offtake leading from said producer, a vent pipe connected with said offtake, a delivery main connected with said offtake, and automatic means for controlling communication of said offtake with said vent pipe or with said delivery main in accordance with the quality of the generated gas, said automatic means comprising a thermostat, a burner having a portion thereof positioned beneath said thermostat and another portion at one side of said thermostat, igniting means for said other portion of said burner, and means for preventing premature burning of gas issuing from said first portion of said burner beneath the thermostat until said gas becomes capable of supporting combustion without the aid of said igniting means.

12. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, means for supplying generated gas to said burner, means coacting with said burner adapted to effect shifting movement of said valve when gas issuing from said burner becomes combustible, a work device, a second burner coacting with said work device, means for supplying generated gas to said second burner, means for automatically igniting the gas issuing from both burners when said gas becomes combustible, said automatic means having mechanism for automatically cutting off the supply of gas to said first burner while maintaining the supply to said second burner when shifting movement of said valve has been effected.

13. Gas generating apparatus of the character described, comprising a gas producer adapted to contain a fuel bed of carbonaceous material, means for blasting said fuel bed to cause the generation of combustible gas, and automatic means for causing intermittent actuation of said blasting means during standby periods to thereby keep the fuel bed in gas-making condition, said automatic means comprising pressure-responsive means for controlling the actuation of said blasting means, a member having a leak orifice in connection with said pressure-responsive means, and means for preventing condensation of moisture in said orifice member.

14. Gas generating apparatus of the char-

- acter described, comprising a gas producer adapted to contain a fuel bed of carbonaceous material, means for blasting said fuel bed to cause the generation of combustible gas, and 5 automatic means for causing intermittent actuation of said blasting means during stand-by periods to thereby keep the fuel bed in gas-making condition, said automatic means comprising means responsive to pressure of 10 said generated gas for controlling the actuation of said blasting means, and a leak tube for said pressure-responsive means positioned in heat-transferring relation with a heated portion of said producer to prevent condensation of moisture within said leak tube.
15. Gas generating apparatus of the character described, comprising a gas producer adapted to contain a fuel bed of carbonaceous material, a gas offtake for said producer, a pump connected with said offtake for blasting said fuel bed to generate combustible gas and for distributing said gas for use, a blast inlet connection for said producer, an inwardly opening check valve with- 20 in said blast inlet connection, a delivery main in communication with said pump outlet, a vent pipe in communication with said pump outlet, and an outwardly opening check valve within said vent pipe.
- 25 16. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means com- 30 prising a burner, means for supplying generated gas to said burner, an expandible and contractible sylphon positioned to be heated by the burning of gas at said burner, a stationary support for one end of said sylphon, 35 a sylphon casing pivotally mounted on a stationary support, a connection between the other end of said sylphon and said sylphon casing, the pivotal mounting of said casing and the stationary support for said one end 40 of the sylphon being so spaced that expanding and contracting movement of said sylphon effects rocking movement of said casing about its pivotal mounting, and an actuating lever for said valve positioned to be 45 contacted by said casing on rocking movement thereof to effect shifting of said valve.
17. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said 50 valve in accordance with the quality of the

generated gas, said automatic means comprising a burner, means for supplying generated gas to said burner, an expandible and contractible sylphon positioned to be heated by the burning of gas at said burner, a stationary support, a stem for one end of said sylphon slidably mounted in said support, a sylphon casing pivotally mounted on said support at a point spaced from said mounting for said stem of the sylphon, a connection between the other end of said sylphon and said casing whereby expanding and contracting movement of said sylphon effects rocking movement of said casing about its pivotal mounting, a spring positioned about said stem and between said stationary support and said sylphon, an actuating lever for said valve positioned to be contacted by said casing on rocking movement thereof, and a locking lever pivoted to said casing to initially restrain actuating movement of said casing, said locking lever having an arm adapted to be held in locking engagement with said stationary support when said sylphon is in contracted position, and having its other arm in engagement with said sylphon whereby a predetermined expanding movement of said sylphon rocks said lever out of locking engagement with said support to effect a sudden shifting movement of said valve. 55

18. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, a connection between said vent pipe beyond said valve and said burner to supply generated gas to said burner only when gas is being discharged to vent, and means in heat responsive relation with said burner for automatically shifting said valve means to close off communication between said offtake and said vent pipe and open communication between said offtake and said delivery main when gas issuing from said burner becomes combustible and burns. 105

19. A gas generating system comprising a gas producer, a gas offtake leading off from said producer, a vent pipe connected with said offtake, a delivery main connected with said offtake, valve means for controlling communication of said offtake with said vent pipe or with said delivery main, and automatic means for controlling the position of said valve in accordance with the quality of the generated gas, said automatic means comprising a burner, a connection between said vent pipe beyond said valve and said burner to supply generated gas to said burner only when gas is being discharged to vent, means 110

- coacting with said burner for automatically shifting said valve means to close off communication between said offtake and said vent pipe and open communication between said offtake and said delivery main when gas issuing from said burner becomes combustible and burns, electric igniting means for igniting the gas issuing from said burner, and a pressure operated switch within the circuit 5 70
- 10 of said igniting means responsive to pressure of gas within said vent pipe and adapted to be closed to energize said igniting means only when gas is being discharged to said vent pipe. 75
- 15 20. A gas generating system comprising a gas producer, a gas offtake leading from said producer, a vent pipe connected with said offtake, a delivery main connected with said offtake, and automatic means for controlling 80
- 20 communication of said offtake with said vent pipe or with said delivery main in accordance with the quality of the generated gas, said automatic means comprising a thermostat, a burner having a portion thereof positioned 85
- 25 beneath said thermostat and another portion at one side of said thermostat, igniting means for said other portion of said burner, and a baffle positioned between said igniting means 90
- 30 and said thermostat and spaced above said burner such that premature burning of gas issuing from said burner beneath said thermostat due to said igniting means is prevented until said gas becomes capable of itself supporting combustion, and the combustible 95
- 35 40 gas then issuing from said burner beneath said thermostat will be ignited through communicating space around said baffle. 100
- 45 21. A gas generating system comprising a gas producer, a gas offtake leading off from 105
- 40 said producer, a vent pipe connected with said offtake, a delivery main connected with said offtake, valve means controlling communication of said offtake with said vent pipe or with said delivery main, and automatic means 110
- 45 for controlling the position of said valve in accordance with the quality of the generated gas, said automatic means comprising a burner, means for supplying generated gas to said burner, means coacting with said burner 115
- 50 adapted to effect shifting movement of said valve when gas issuing from said burner becomes combustible and burns, said automatic means having mechanism for automatically cutting off the supply of gas to said burner 120
- 55 when shifting movement of said valve has been effected, igniting means for said burner, and automatic means for operating said igniting means only when gas is being supplied to said burner. 125
- 60 22. Gas generating apparatus of the character described, comprising a gas producer adapted to contain a fuel bed of carbonaceous material, means for blasting said fuel bed to cause the generation of combustible gas, 130
- 65 and automatic means for causing intermittent 130
- actuation of said blasting means during stand-by periods to thereby keep the fuel bed in gas making condition, said automatic means comprising means responsive to pressure of said generated gas for controlling the actuation of said blasting means, a leak tube, piping connecting said leak tube and said pressure responsive means, and a condensate trap within 70

said pump is operating and forcing generated gas through said vent pipe and being automatically closed when said pump is stopped.

- 5 26. Gas generating apparatus of the character described, comprising a gas producer adapted to contain a fuel bed of carbonaceous material, an offtake leading from said producer, a pump connected to said offtake for
10 blasting said fuel bed to generate combustible gas and for distributing said gas for use, a blast inlet connection for said producer through which air is drawn in under suction during operation of said pump, and an in-
15 wardly opening check valve within said blast inlet connection to prevent back flow of gas from said producer through said blast inlet connection when said pump is not operating, said valve being automatically opened when
20 said pump is operated and being automatically closed when said pump is stopped.

27. Gas generating apparatus of the character described, comprising a gas producer adapted to contain a fuel bed of carbonaceous
25 material, a pump for blasting said fuel bed to generate combustible gas and for distributing said gas for use, an electric motor for driving said pump, a relatively high voltage electrical supply line, means for connecting
30 said motor circuit to said supply line to furnish high voltage current to said motor, an electrical control circuit for controlling operation of said gas generating apparatus, a voltage reducing means, and means for connecting said control circuit to said supply line through said voltage reducing means to thereby supply relatively low voltage to said control circuit.

- 35 28. In gas generating apparatus of the character described, and having a gas producer adapted to contain a fuel bed of carbonaceous material, and means for blasting said fuel bed to cause the generation of combustible gas; a gas offtake for the producer, a
40 delivery line connected with said offtake for leading the generated gas to a place of use, a vent pipe connected with said offtake, valve means for controlling the distribution of generated gas to said delivery line or to said
45 vent pipe, means for controlling the positioning of said valve means, an electric circuit, a switch therein, and pressure operated means responsive to pressure of generated gas on the vent pipe side of said valve means for
50 controlling opening and closing of said switch.

In testimony whereof I hereunto affix my signature.

HARRY F. SMITH.
